UNITED STATES PATENT OFFICE.

JOSEPH HREN, OF ROSENDALE, NEW YORK, AND CARL EISENLOHR, OF NEWARK, NEW JERSEY.

CLUTCH MECHANISM.

Application filed May 22, 1920. Serial No. 383,556.

To all whom it may concern:

Be it known that we, JOSEPH HREN and CARL EISENLOHR, citizens of the United States, residing at Rosendale, New York, and Newark, New Jersey, respectively, have invented a new and useful Improvement in Clutch Mechanism, of which the following is a specification.

This invention relates to clutch mechanism, the object being to provide a clutch of simple construction adapted for effective use in all work and for all uses and under all conditions in which a clutch can be employed, and which is particularly adapted to the conditions of operation and use as set forth in a patent granted to us February 11, 1919, No. 1,293,782, machine for making paper box blanks, in which a box blank is formed out of three sections, viz:—a main section and two wing sections pasted thereto.

In the operation of the above described machine the cardboard blanks are fed from magazines, and during the feeding movement the wing sections have an adhesive applied to their inner edges after which the main section is lapped over the wing sections and attached one to the other by pressure and the principal object of our improved clutch mechanism is to provide means to automatically stop the above described machine when the main magazine is empty or when two or more sheets are fed into the machine at one time.

To these ends, and to such others as the invention may pertain, the same consists, further, in a novel construction, combination and adaptation of the parts, as will be hereinafter more fully described and then specifically defined in the appended claims.

In the drawings, similar reference characters are employed to designate corresponding parts throughout the views, in which:—

Fig. 1 is a side elevation, in part section, of a portion of a machine for making paper box blanks, and showing the drive and stop mechanism.

Fig. 2 is an enlarged central section of the clutch.

Fig. 3 is a section on the line 3—3 of Fig. 2.

Fig. 4 is a section on the line 4—4 of Fig. 2.

Fig. 5 is a section on the line 5—5 of Fig. 3.

Referring to Fig. 1 of the drawings, we

show at 10, a supporting table on which cardboard blanks 11 are held in a suitable magazine 12.

In practice there are three magazines side by side, but for the purpose of this description the showing of the central magazine holding the main blanks will suffice.

The cardboard blanks are fed out of the magazine 12, one at a time, by pusher blocks (not shown) and are drawn between feed rolls 13 and 14, and pass downwardly onto a pressure table 15, supported by springs 16, over which is arranged a presser foot 17, carried on an eccentric 18, mounted on the clutch shaft 19, as shown.

A motor 20, is shown geared to a reducing train 21, in mesh with clutch gear 22, which is fast on a hub 23, normally loose on shaft 19. Opposite to this hub there is threaded upon shaft 19, a collar 24, having a plurality of beveled chambers 25.

Between hub 23, and collar 24, is placed a cage-disk 26, having a corresponding number of slots 27, to receive friction rolls 28.

Cage-disk 26, is also provided with a segmental slot 29, against an end wall of which abuts one end of a spiral spring 30, the other end of which bears against a pin 31, carried by collar 24. This spring tends to so turn the latter, that friction rolls 28, are forced into the contracted portions of chambers 25, so that the rolls by bearing against cage-disk 26, will force the latter into facewise contact with the hub 23, and close to the clutch.

Cage-disk 26 is provided with a shoulder 32, adapted to be engaged by either of two dogs 33 and 34, pivoted to the machine frame (not shown). When either of the dogs are swung into the path of the shoulder 32, they will, upon the rotation of shaft 19, come into engagement with said shoulder, so that during the further slight movement of the shaft, cage-disk 26, will remain arrested, against the action of spring 30. The cage-disk will thus become so placed relatively to collar 24, that friction rolls 28, are made to face the expanded portion of chambers 25, and will consequently recede into said chambers and away from cage-disk 26. The pressure of the latter against hub 23, will thus relax so that the clutch is opened or disengaged, and shaft 19 will no longer participate in the rotation of the motor shaft as will be readily understood.

As the cardboard sheets 11, pass from the magazine, in rapid succession, they pass under and elevate a roller 35, carried on a pivoted lever 36, bearing against a rod 37, connected to a bell crank lever 38, which is linked as at 39, to the dog 33, and the continuous passage of the cardboard sheets from the magazine holds the roller 35, in a constantly elevated position which acts to force the nose of dog 33, out of the path of the rotating shoulder 32, but should the feed from the magazine stop, the roller 35, will drop and spring 40, will draw dog 33, to the right and into the path of shoulder 32, and the machine will be stopped.

As above stated when forming composite box blanks the edges of the several sections are glued and subjected to pressure and we have provided automatic tripping means, adapted to be operated as the pressure is applied, which comprises an arm 41, pivoted to the machine at 42, and to a bar 43, which is spring pulled upwardly as at 44, to hold arm 41, in constant engagement with an adjustable screw 45, threaded through the yielding pressure table 15.

The bar 43, has a nose 46, normally engaging a tail-piece 47, formed on the dog 34, which is pivoted at 48, to the machine frame (not shown) and a pull spring 49 holds tail piece 47, against nose 46, and at each downward movement of the presser foot 17, the table 15 is forced down slightly against the action of springs 16, but not enough to cause nose 46, to clear tail piece 47, when but one main blank is under presser foot 17, but should the feed go wrong and two or more blanks are fed at once the additional thicknesses between pressure table and presser foot will cause table 15, to descend further than the normal limit and draw nose 46, out of contact with tail piece 47, and allow spring 49 to force dog 34, over into the path of the rotating shoulder 32, and the machine will be stopped, after which the dog 34, may be reset by grasping the handle 50.

It is thought that the operation and utility of the device will be apparent without further description, and while in the drawings there is illustrated a preferred embodiment of the invention, it is to be understood

that the structural elements thereof are susceptible to such variations and modifications as fall within the scope of the appended claims.

What we claim is:—

1. In a stop mechanism for a machine having a magazine and a presser table comprising a pair of dogs, trip devices positioned one at the mouth of the magazine and one at the presser table of the machine, connections between said dogs and said trip devices, in combination with a clutch having a shoulder to engage either of said dogs to stop the machine as described.

2. In a stop mechanism for a machine having a magazine and a presser table comprising a no-feed tripping device placed at the mouth of the magazine, a multiple-sheet tripping device on the presser table of the machine, a pair of dogs, a train of links engaging said tripping devices and dogs, in combination with a clutch having a shoulder to engage either of said dogs to stop the machine as described.

3. In a stop mechanism for a machine having a magazine and a presser table, a clutch, a no feed trip device positioned at the mouth of the magazine, a multiple sheet trip device on the presser table and means operated by said trip devices to engage the clutch to stop the machine as described.

4. In a stop mechanism for a machine having a magazine and a presser table, a clutch, trip devices positioned at the mouth of the magazine and on the presser table, and means operated by the trip devices to engage the clutch to stop the machine as described.

5. In a stop mechanism for a machine having a magazine and a presser table, a tripper positioned to be operated by sheets discharged from the magazine, a tripper on the presser table, a clutch, and means operated by the said trippers to engage the clutch and stop the machine as described.

In testimony whereof, we have signed our names to this specification this 24th day of April, 1920.

JOSEPH HREN.
CARL EISENLOHR.
